TOY BELT-FED MACHINE GUN AND
CARTRIDGE THEREFORJoseph L. Bonanno, South Orange, N.J., assignor to
De Luxe Reading Corp., Elizabeth, N.J., a corpora-
tion of New JerseyFiled Feb. 17, 1965, Ser. No. 433,356
15 Claims. (Cl. 124—29)

ABSTRACT OF THE DISCLOSURE

Each cartridge carried by flexible web comprises frictionally engaged projectile and shell. Web and cartridges advanced through gun housing by a peripherally-notched wheel. At firing position, a spring pressed hammer strikes rear of projectile and propels it through gun barrel. Hammer is cocked by second wheel carrying a projection. A second spring pressed hammer strikes shell laterally to eject it from gun housing. Second hammer cocked by projections on notched wheel. Section of barrel is reciprocable. A single spring provides power for rotating wheels and reciprocating barrel section in timed relation.

This invention relates generally to toys, and has particular reference to an improved toy machine gun.

It is a general object of the invention to provide a lightweight relatively inexpensive article which is exteriorly a realistic simulation of an actual machine gun, and is provided with improved mechanism for firing a succession of projectiles.

A more specific objective of the invention is to provide an apparatus of trigger-actuated variety, adapted to accommodate and advance a belt which carries simulated ammunition, to fire a succession of projectiles forwardly through the barrel of the gun, and to follow each firing of a "bullet" with a realistic lateral discharge of a "shell."

A further objective of the invention is to provide a toy machine gun in which the simulation of the actual gun includes a mount in the nature of a tripod, means for rotating the gun on a vertical axis through a full 360 degrees, and means for swinging the gun in a controlled manner about a horizontal axis to vary the angularity at which the projectiles are discharged from the barrel.

It is a feature of the invention to provide, in addition, a simulation of the recoil of a real gun, this result being achieved by providing a forward barrel section that is mounted for axial reciprocation, and a means operated in timed relation to the firing of the gun for reciprocating this barrel section.

Another feature of the invention resides in the fact that the operation is entirely spring-operated, requires no batteries nor electrical connections of any kind, and is so designed, both structurally and operationally, that despite its sinister aspect it is quite harmless.

Among the features of the invention which contribute to its utilization as a harmless toy is the design and construction of its several parts of light-weight molded plastic, and the employment of "cartridges" each of which consists of a light-weight plastic projectile associated in a novel frictional manner with a similar light-weight element simulating a shell, the impact of the propelled elements being of harmless magnitude and character.

Another feature of the invention, contributing to the realism of the simulation and the attractiveness of the toy, is the provision of a special flexible apertured element in the form of a plastic web or belt with which the cartridge assemblies (each composed of a projectile and shell-simulating cylinder) can be readily mounted in parallel array; and the provision of a gun stock with a guide housing into which this cartridge-carrying web or belt can be

2

inserted and then advanced in realistic fashion as the gun is fired.

The actuating mechanism comprises, in brief, a means for supporting each projectile in alignment with the gun barrel, a spring-pressed means for striking the projectile to propel it forwardly through and out of the barrel, another spring-pressed striking means for propelling each shell element laterally after the projectile has been separated from it, a common main spring for activating these strikers, a means for stressing the main spring and retaining it in releasable fashion in its stressed condition, and a trigger for releasing the main spring and allowing it to activate the projectile striker and the shell striker in timed relationship. Also actuated by the main spring is mechanism that advances the cartridge-carrying belt laterally in predetermined manner to present the supported projectiles in succession to the firing means.

A basic general objective of the invention is to provide the operating mechanism in the form of a relatively simple, inexpensive, and compact unit, to house this unit in a manner which shields it and assures reliable operation over long periods of time and which at the same time shields the user from any contact therewith, and to design the several parts of the toy in such a way that they can be feasibly manufactured at low cost on a commercial scale and readily assembled into a staunch and wear-resistant plaything.

One way of achieving these general objects and advantages, and such other advantages as may hereinafter appear or be pointed out, is shown in the accompanying drawings in which:

FIG. 1 is an exploded view of a toy gun assembly embodying the features of this invention;

FIG. 2 is a fragmentary side view, partly in section, of the rear end of the gun including the trigger and rear sight;

FIG. 3 is a similar view of the "breech" region;

FIG. 4 is a similar view of the front end including the front sight;

FIG. 5 is a similar view of the gun support in the region below FIG. 3;

FIG. 6 is a cross-sectional view along the lines 6—6 shown on FIGS. 3 and 5;

FIGS. 7 and 7a are details along corresponding lines on FIG. 6;

FIG. 8 is a side view of the "breech" region, with parts broken away to reveal the main spring and actuating rack;

FIG. 9 is a plan view in the direction 9—9 of FIG. 8, with the top wall of the guide housing closed;

FIG. 10 is a similar view along the line 10—10 beneath the top wall;

FIG. 11 is an enlarged fragmentary cross-section on line 11—11 of FIG. 8;

FIG. 12 is a perspective view of some of the drive mechanism;

FIG. 13 is a plan view of the drive mechanism;

FIGS. 14 and 14a are elevational views along the line 14—14 of FIG. 13 showing successive operating positions;

FIGS. 15 and 15a are similar views in the opposite direction, along the line 15—15 of FIG. 13;

FIGS. 16, 17 and 18 are fragmentary schematic views along the line 16—16 of FIG. 14, showing successive operating positions;

FIG. 19 is an exploded view of the "cartridge" unit and part of the carrier belt;

FIG. 20 is a top view of the elements of FIG. 19 in assembled relation; and

FIG. 21 is a cross-sectional view on line 21—21 of FIG. 20.

The gun may be used in any position, and may be carried by the user or supported on a stand. An illustrative

mount is shown in FIG. 1, comprising a platform 30 to which legs 31 are pivotally connected, and a support element 32 rotatable on the platform about a vertical axis and provided with upstanding spaced ears 33. Mounted between the ears on a horizontal spindle 34 is a swingable element 35 having a hub 36 for support on the spindle 34, an upper bracket portion 37 for securing to the gun itself (e.g., by bolts 38 extending through pierced lugs 39), and a lower exteriorly toothed gear segment 40. The latter meshes with an actuating pinion 41 mounted on a shaft 42 journaled in bearings 43 on the element 32. The shaft 42 carries a control handle or crank 44 whose rotation adjusts the gun to selected different angularities with respect to the platform 30. The shaft 42 is mounted for axial shifting (FIG. 7a) and carries a non-circular (e.g., squared) portion 45 adapted to be selectively locked with or withdrawn from a similarly shaped recess 46 in the adjacent bearing 43. This allows the gun to be locked at any of a number of different angles since rotation of the shaft 42 is prevented whenever the part 45 is shifted into registry with the recess 46 (see FIG. 7).

The individual parts of this supporting structure, and of the gun itself, may be advantageously composed of molded light-weight plastic, since this lends itself in known fashion to selected pigmentation and to the realistic simulation in considerable detail of actual gun mounts and gun parts, whereby the attractiveness of the toy is enhanced.

The gun itself comprises a rear part having spaced handles 47 (FIG. 2) and a depressible trigger 48 between them; a hollow medial gunstock region (FIGS. 3 and 8) composed preferably of two longitudinal halves joined by transverse bolts; and a forward part 50 containing the barrel of the gun, including a front barrel portion 51 (FIG. 4) mounted for axial reciprocation, and a rear fixed barrel part 52.

The rear part of the gun may be provided with a rear sight 53, and the forward part 50 may carry a front sight 54.

Directly behind the rear end 55 of the fixed barrel part 52 (see FIG. 3), the gunstock is provided with a hollow region or housing 56 (FIG. 6) through which cartridge units 57 (see FIG. 1) can be brought successively into a firing position in alignment with the gun barrel. The top wall 134 of the housing is pivoted to the gunstock at 135 and releasably latched at 136 so that access to the interior is readily available. An opening or pasageway 78 (FIGS. 6 and 9) is formed in the top wall 134 for a purpose presently to be described. A special flexible carrier or belt 58 moves into the housing 56 through an inlet opening at one side (the near side as seen in FIG. 1 and the right side in FIG. 6); is guided through the housing; and leaves the housing through an outlet opening on the opposite side.

The cartridge belt and the nature of the units it carries are shown best in FIGS. 1, 6, 19, 20, and 21.

Each "cartridge" comprises a projectile and a cylindrical element with which it can be frictionally assembled in readily separable relation. The projectile 59 is shown at the right of FIG. 19, the "shell" element 60 at the left. The projectile is preferably of circular cross-section and has an enlarged head 61, preferably blunt or rounded at its front end. Extending rearwardly from the head 61 is a stem 62 of reduced diameter having a blunt flat rear end. Surrounding the stem 62, preferably in the region directly behind the head 61, are small enlargements or ribs 63. The entire projectile is a single element of light-weight plastic molded to the configuration described. The cylindrical element 60, also a single molded piece, is essentially a sleeve whose outer diameter is substantially the same as that of the projectile head 61 and whose inner diameter is slightly greater than that of the projectile stem 62, whereby the forward part of the sleeve can be frictionally fitted over the ribs 63 as shown in FIG. 20. The rear end of the element 60 has a flange 64. The length

of the cylinder 60 is less than that of the projectile stem 62 so that when the parts are assembled the rear end of the stem 62 will project rearwardly as shown in FIG. 20.

The flexible carrier 58 is an integral element of flexible plastic configured to define a part which may be termed a "web" 65, and fins 66 and 67 (see FIGS. 6 and 21) projecting outwardly on opposite sides of the web. Conjointly the fins 66 and 67 define a center rib extending in the longitudinal direction of the carrier 58. This rib serves as a guide for the carrier during its movement through the gun, being guided by the opposed upper and lower grooveways 68 and 69 (FIGS. 6 and 8) in the housing. To facilitate the introduction of the carrier into the housing the grooveways may be flared outward at their inlet ends, as shown in FIGS. 8, 9, and 10.

The rib defined by the fins 66 and 67 also serves as a holder for the "cartridges." It will be noticed that the web 65 is shaped to provide a succession of substantially semi-cylindrical depressions 70 (FIG. 21) connected by planar areas 71. Each depression 70 has an inner curvature corresponding to that of the cartridge unit so that the latter may be cradled in it.

The fins 66 and 67 are formed in pairs on the web 65 only in the region of each convexity 70, and they are separated in the planar areas 71, thus allowing the carrier 58 to flex in these planar areas.

Each fin 66 on the upper side of the web 65 is provided with a circular aperture 73 whose diameter is larger than that of the projectile stem 62 but less than that of the projectile head 61 and sleeve element 60. When the "cartridge" units are loaded onto the carrier, each unit rests in one of the depressions 70 and is brought to this condition by passing the projectile stem 62 rearwardly through one of the apertures 73 and then applying the sleeve element 60 to it. The frictional interengagement of the parts positions the projectile head 61 on the forward side of the center rib and the shell 60 on the other.

As the "ammo" belt or carrier is fed into the gun stock by introducing the rib into the grooveways 68 and 69, the semi-cylindrical depressions 70 come into engagement successively with recesses 74 on the periphery of a wheel 75 (see FIGS. 6, 12, 16, 17, 18). The rotation of this wheel in a manner presently to be described serves to advance the cartridge carrier through the guide housing. During its travel it brings the cartridge units successively into alignment with the gun barrel 52. One such unit is shown in this location in FIG. 3. At the moment of each such alignment the firing mechanism functions to cause the front end of rod 76 (see FIGS. 3, 14, and 15) to strike the rear end of the projectile stem 62 and thus separate the projectile 59 from the shell 60 and propel it forwardly through the gun barrel. Almost immediately thereafter the released shell element 60 is struck laterally, i.e., upwardly, by the striker 77 (FIGS. 6, 16, 17, 18) and thus propelled out of the top opening 78 (FIGS. 3 and 6) of the guide housing 56. The flange 64 at the rear end of the shell 60 can be guided along the rib 137 on the floor of the housing 56 before the shell is struck.

The activation of the hammer rod 76 and striker 77 (and of the reciprocable barrel part 51) is controlled by a main spring which can be stressed by a simple external adjustment, releasably retained in stressed condition, and released at will by pressure upon the trigger 48. The spring is a coiled compression spring 79 mounted upon a rod 80 extending lengthwise within the hollow gun stock along one of the side walls. This wall is designated 72 in FIG. 11. The spring 79 is preferably pre-stressed so as to minimize the change of force available for actuating the mechanism, i.e., the force exerted by the spring after it has been fully loaded and fully released is substantially uniform.

Mounted parallel to the rod 80 is a toothed rack 81 slidably in its axial direction. At its front end, the rack 81 carries a projection 82 (FIG. 8) which is looped

around the rod 80 in front of the spring 79. Rearward movement of the rack thus compresses and stresses the spring 79.

The guidance of the rack 81, and its connection to the actuating knob 83 on the exterior of the housing, is shown in FIG. 11. The knob 83 is rigidly secured to a stem 84 carried by the rack 81 and projecting laterally through a slot 85 in the housing wall 72. The stem 84 is secured to a guide piece 86 which rides on the exterior face of the wall 72, and the rack is formed with a part 87 which is similarly guided along the inner face of the wall. The teeth of the rack 81 mesh with a drive pinion 88. Through this pinion the force of the stressed spring 79 is transmitted to the mechanism. This mechanism can best be explained by reference to FIGS. 12, 13, 14 and 15.

The gears, shafts, and other elements are mounted in any suitable fashion within an appropriate frame 89 of rigid material such as metal. The pinion gear 88 is mounted at the end of a transverse shaft 90 and is in constant mesh with the teeth of the rack 81. Mounted on the shaft 90 in concentric relation thereto, but freely movable with respect to the shaft, is a sleeve 91 carrying a small-diameter spur gear 92 at one end and a relatively large-diameter spur gear 93 at the other end. The large gear 93 is formed on its outer surface (see FIG. 15) with a plurality of (preferably two) inclined portions 94 arranged along an arc concentric with the shaft axis. Each inclined portion terminates in an abrupt shoulder 95. These formations are the equivalent of ratchet teeth. They cooperate with an element 96 serving the function of a pawl which is secured to the shaft 90 and is constantly urged by spring 97 into rubbing contact with the face of the gear 93. The pawl element 96 carries parts adapted to ride up the inclined portions 94 on the gear 93 whenever the shaft 90 is rotated in one direction (counter-clockwise in FIG. 15), whereby this rotation of the shaft transmits no power to the gear 93. On the other hand, the pawl element parts engage the abrupt abutment faces 95 on the gear 93 when the shaft 90 is rotated in the opposite (or driving) direction, whereby the shaft 90 imparts a corresponding rotation to the gear 93. More specifically, as viewed in FIG. 12 when the pinion 88 and shaft 90 are rotated in a clockwise direction, the pawl 96 rides ineffectively up the inclines 94 on the gear 93 and the latter remains stationary; but when the shaft 90 is rotated in a counter-clockwise direction (i.e., whenever the stressed spring 79 is allowed to impose its force upon the pinion 88) the pawl disc 96 presses against the shoulders 95 on the gear 93 and causes it to be driven in a counter-clockwise direction.

The gear 93 carries, on its inner face, a plurality of camming discs 98, arranged along an arc concentric with the shaft axis. Each camming disc 98 is preferably a circular disc adapted to encounter and bear against the front edge 99 of a flat pivoted spring stresser element 100. This element has a flat part in a longitudinal plane, presenting a sharp front edge 99, and another part in a transverse plane. It is adapted to pivot on a transverse horizontal axis 101 at its lower end, and whenever the gear 93 is rotated and one of the camming discs 98 encounters the edge 99, the element 100 is swung into the position shown in FIGS. 14a and 15a. This swinging movement is accomplished against the constanturgence of a spring 102 which is anchored at one end to the supporting frame 89 and at the other end to the pivoted element 100.

The upper edge of the transverse part of the element 100 is normally positioned in front of a tooth 103 on a pivoted keeper 104 (FIGS. 14 and 15). This keeper is pivoted at 105 to the rear end of the longitudinal hammer rod 76 which is aligned with the gun barrel 52. Adjacent to its forward end this rod is provided with a flange 106 and between this flange and a part of the frame 89 is a compression spring 107. Whenever one

of the camming discs 98 pushes the pivoted element 100 into the position shown in FIG. 14a the rod 76 is pulled rearwardly against the urging of the compression spring 107. This is the "hammer" for striking the projectile 59 and propelling it forwardly through the gun barrel, and the compression of the spring 107 is the manner in which energy is stored up to permit the striking of the projectile to take place suddenly and with adequate force. The release of the hammer rod 76 comes about by virtue of the fact that the pivoted element 100 slides out from beneath the tooth 103 of the keeper 104. This brings about a sudden release of the compressed spring 107, and as it expands it drives the rod 76 forwardly in a sudden manner and the pressure of the forward end of this rod against the rear end of the projectile 59 causes the latter to be propelled forcibly forward through the gun barrel.

As each camming disc 98 reaches its rearmost position (as the gear 93 continues to rotate) and then starts moving in a forward direction, the spring 102 swings the element 100 back to its normal position (FIG. 14). The element 100 resumes its position in front of the tooth 103 on the keeper 104 by virtue of the fact that it cams the keeper out of the way, temporarily, against the urging of the light spring 108 which tends constantly to maintain the keeper 104 in the full-line position shown in FIG. 14.

The tensioning and sudden release of the spring 107 takes place each time a camming disc 98 moves rearwardly against the front edge 99 of the pivoted element 100. In the mechanism illustrated, there are two camming discs 98, arranged at diametrically opposite points on the gear 93. Thus, for each rotation of the gear 93 there are two activations of the striking means for the projectile 59.

The striking means for the released shell element 60 is similarly activated by a spring which is tensioned and then suddenly released. This spring 109 extends between a fixed point on the frame 89 and the spring stresser 110 of the striking lever 77. The latter is mounted for pivotal movement on a longitudinal spindle 111 (see FIGS. 16-18). The other arm of the lever 77 is formed as a striking head, and in an intermediate part of the lever 77 there is a forward projection 112 serving as a cam follower. The means for exerting a camming pressure on this follower is a series of circumferentially arranged arcuate projections 113 on the rear face of wheel 75. This wheel is mounted at the forward end of a longitudinal shaft 114. At the rear end of this shaft is a rearwardly-facing crown gear 115 which meshes with a spur gear 116 on a transverse shaft 117. Interposed between the gear 116 and the gear 92 of the sleeve element 91 is an intermediate transmission gear 118. Whenever the gear 93 is driven (as hereinbefore described) the meshing of the gears 92, 118, 116, and 115 brings about a rotation of the wheel 75. During this rotation, as each arcuate projection 113 encounters the cam follower projection 112 it rocks the striking lever 77 into the position shown in FIG. 17, thereby tensioning the spring 109, and as each projection 113 reaches the point at which it slides away from beneath the projection 112, the spring 109 becomes effective to suddenly return the striking lever 77 to the position shown in FIG. 16. This causes the striking head to hit the shell cylinder 60 of the "cartridge" and propel it laterally out of the opening 78 in the housing 56 (FIG. 18).

As previously mentioned, the periphery of the wheel 75 is formed with a succession of concavities 74 adapted to fit with the successive convexities 70 of the web part 65 of the cartridge belt 58. The gears are so designed that the cartridge belt 58 is advanced in timed relation to the operation of the two striking mechanisms, whereby the projectile 59 of each cartridge is first struck by the front end of the hammer rod 76, and immediately thereafter the striking head of the lever 77 strikes the released shell cylinder 60.

Also actuated by the gear 93 when it is rotated is the smaller gear 119 formed at one end of a sleeve 120

mounted for free rotation on a transverse shaft 121. At one end of this sleeve it is provided with the crank arm 122 to which is linked the rear end of a rod 138 which is in turn linked to the forwardly-extending rod 123 which controls the reciprocation of the front section 51 of the gun barrel (see FIG. 4). Preferably the opposite end of the sleeve 120 is formed with a toothed part 124 which cooperates with one end of a rocker element 125. This element serves to dampen the rotation of the sleeve 120 during the brief time intervals following the firing of each projectile and preceding the next rearward camming of the pivoted element 100.

The mechanism is normally held in a deactivated condition by the latching lever 126. (See FIGS. 15 and 15a.) This lever is pivoted at 101 and its rear end is articulated at 128 to the connector 129 which is carried at the forward end of the pivoted trigger arm 130. The rear end of the arm 130 constitutes the trigger 48, and whenever the latter is depressed, the connector 129 is pulled up as indicated by dotted lines in FIG. 3. At the forward end of the latching element 126 it is provided with an edge recess 131 adapted to come into releasable engagement with one of several projections 132 arranged along a concentric arc on a face of gear 93. A tension spring 133 normally urges the forward end of the latching lever 126 into an upward disposition (FIG. 15), whereby the gear 93 is locked against movement.

When the spring-stressing knob 83 is moved rearwardly to increase the tension of the main spring 79, the rack 81 rotates the main driving gear 88 but this rotation has no effect upon any of the other mechanism, because the pawl elements 96 ride freely over the inclined projections 94 on the gear 93. The mechanism remains inactive, even after tensioning of the spring 79, because of the engagement of the latching lever 126 with one of the projections 132 on the gear 93. However, pressure exerted upon the trigger 48 serves to lift the rear end of the latching lever 126 and release the front end from the projection 132 on the gear 93. This allows the stressed spring 79 to transmit its power through the gear 88 and the "ratchet teeth" 95 to the gear 93 whereby the two striking mechanisms and the barrel-reciprocating mechanism are actuated in timed relation as hereinbefore described. The mechanism comes to a halt as soon as the spring 79 has expanded to the maximum possible extent, and a recharging of this spring by means of knob 83 is then necessary before further activation is possible.

Many of the structural details described and illustrated may obviously be modified without necessarily departing from the spirit and scope of the invention as expressed in the appended claims.

What is claimed is:

1. A toy gun comprising:

- (a) a hollow part simulating a gun stock and supporting a barrel with its rear end accessible,
- (b) a simulated cartridge comprising a projectile and a simulated shell separably associated with it,
- (c) means for supporting the cartridge in a firing position adjacent to the rear end of the barrel, said means including a flexible web carrying a series of said cartridges in side-by-side relation along its length,
- (d) means for striking the projectile to separate it from the shell and propel it through the barrel,
- (e) means for striking the separated shell to propel it laterally,
- (f) means for advancing said web longitudinally to bring successive cartridges to the firing position, and
- (g) a common spring-powered drive mechanism within said gun stock for activating said striking means (d) and (e) and said web-advancing means (f).

2. A toy gun as defined in claim 1, in which said drive mechanism comprises

a spring,
means on said gun stock for stressing said spring,

a detent for releasably retaining said spring in stressed condition, and

a trigger on said gun stock for releasing said detent.

3. A toy gun as defined in claim 1, in which said drive mechanism comprises

a pre-stressed compression spring mounted on a rod extending lengthwise through the spring, means on said gun stock for further stressing said spring, and releasable means for retaining said spring in said further stressed condition.

4. A toy gun comprising:

- (a) a barrel, said barrel comprising a means which includes a forward section mounted for axial reciprocation,
- (b) a simulated cartridge comprising a projectile and a simulated shell separably associated with it,
- (c) means for supporting the cartridge in a firing position adjacent to the rear end of the barrel,
- (d) means for firing the gun by striking the projectile to separate it from the shell and propel it through the barrel,
- (e) means for striking the separated shell to propel it laterally, and
- (f) means for reciprocating said barrel forward section when the gun is fired.

5. A toy gun comprising:

- (a) a barrel,
- (b) a simulated cartridge comprising a projectile and a simulated shell separably associated with it,
- (c) means for supporting the cartridge in a firing position adjacent to the rear end of the barrel,
- (d) means for firing the gun by striking the projectile to separate it from the shell and propel it through the barrel,
- (e) means for striking the separated shell to propel it laterally, and
- (f) a common spring-powered drive mechanism for activating said striking means (d) and (e) in timed relation.

6. A toy gun comprising:

- (a) a barrel,
  - (b) a simulated cartridge comprising a projectile and a simulated shell separably associated with it,
  - (c) means for supporting the cartridge in a firing position adjacent to the rear end of the barrel,
  - (d) means for firing the gun by striking the projectile to separate it from the shell and propel it through the barrel, and
  - (e) means for striking the separated shell to propel it laterally,
- each of said striking means (d) and (e) comprising a spring pressed hammer, and means for stressing and suddenly releasing said spring, said means comprising
- a spring stresser mounted for oscillating movement,
  - a cam surface carried by said spring stresser, and
  - a rotatable drive shaft carrying a cam adapted to press against said cam surface in opposition to the urging of said spring.

7. A toy gun comprising:

- (a) a hollow part simulating a gun stock and supporting a barrel with its rear end accessible,
  - (b) a simulated cartridge comprising a projectile and a simulated shell separably associated with it,
  - (c) means for supporting the cartridge in a firing position adjacent to the rear end of the barrel,
  - (d) means for striking the projectile to separate it from the shell and propel it through the barrel,
  - (e) means for striking the separated shell to propel it laterally, and
  - (f) a common spring-powered drive
- each of said striking means (d) and (e) comprising

a spring-pressed hammer and means for stressing and suddenly releasing the spring of each spring-pressed hammer on successive occasions, each of said means comprising a spring stresser mounted for oscillating movement and a rotating shaft carrying a series of circumferentially spaced cams adapted to engage said stresser in succession and move it against the urging of said spring, and in which said drive mechanism is articulated to said shafts for rotating the cams continuously.

5

8. A toy gun comprising:

- (a) a barrel,
- (b) a simulated cartridge comprising a projectile and a simulated shell separably associated with it,
- (c) means for supporting the cartridge in a firing position adjacent to the rear end of the barrel, said cartridge supporting means comprising a guide housing, and an apertured element insertable into said housing for engagement thereby, said cartridge being supported within said aperture, said apertured element comprising a web perpendicular to the gun barrel axis, an apertured fin on said web, said projectile and shell lying on opposite sides of said fin, the projectile having a stem extending through said aperture into association with said shell,
- (d) means for firing the gun by striking the projectile to separate it from the shell and propel it through the barrel, and
- (e) means for striking the separated shell to propel it laterally.

10

9. A toy gun comprising:

- (a) a barrel,
- (b) a simulated cartridge comprising a projectile and a simulated shell separably associated with it, said shell being a cylindrical element and said projectile having a stem extending rearwardly through and beyond said element, said projectile stem and shell being configured to interlock in frictional, readily separable, relationship,
- (c) means for supporting the cartridge in a firing position adjacent to the rear end of the barrel, said cartridge supporting means comprising a guide housing provided with an inlet opening, an outlet opening, and a shell-discharge opening, and a web having an apertured fin therein movable into and out of said housing through said inlet and outlet openings, said projectile and shell lying on opposite sides of the aperture in said web and said projectile stem extending through the aperture in said web into interlock with said shell,
- (d) means for firing the gun by striking the projectile to separate it from the shell and propel it through the barrel, and
- (e) means for striking the separated shell to propel it laterally.

30

10. A toy gun as defined in claim 4, including also:

- (g) a common spring-powered drive mechanism for activating said striking means (d) and (e), and said reciprocating means (f), in timed relation.

50

11. A toy gun as defined in claim 6, in which said cam comprises a wheel secured to said shaft, and a series of circumferentially spaced camming elements carried by said wheel and adapted successively to press against said cam surface and thus bring about a succession of spring stressing and releasing movements of said stresser.

65

12. A toy gun comprising:

- (a) a barrel,
- (b) a simulated cartridge comprising a projectile and a simulated shell separably associated with it,
- (c) means for supporting the cartridge in a firing position adjacent to the rear end of the barrel, said means including a flexible web carrying a series of said cartridges in side-by-side relation along its length,
- (d) means for firing the gun by striking the projectile

70

75

to separate it from the shell and propel it through the barrel,

- (e) means for striking the separated shell to propel it laterally, and
- (f) means for advancing said web longitudinally in timed relation to the operation of means (d) and (e) to bring successive cartridges to the firing position,
- (g) each of said striking means (d) and (e) comprising a spring-pressed hammer, and means for stressing and suddenly releasing said spring.

13. A toy gun comprising:

- (a) a barrel,
- (b) a simulated cartridge comprising a projectile and a simulated shell separably associated with it,
- (c) means for supporting the cartridge in a firing position adjacent to the rear end of the barrel, said means including a flexible web carrying a series of cartridges in side-by-side relation along its length,
- (d) means for firing the gun by striking the projectile to separate it from the shell and propel it through the barrel,
- (e) means for striking the separated shell to propel it laterally,
- (f) means for advancing said web longitudinally to bring successive cartridges to the firing position, and
- (g) means for activating said striking means (d) and (e) and said web-advancing means (f) in timed relation,
- (h) each of said striking means (d) and (e) comprising a spring-pressed hammer and means for stressing and suddenly releasing said spring, and said activating means (g) comprising a drive mechanism adapted to release the projectile activating spring first.

14. A toy gun comprising:

- (a) a barrel,
- (b) a simulated cartridge comprising a projectile and a simulated shell separably associated with it,
- (c) means for supporting the cartridge in a firing position adjacent to the rear end of the barrel, said means including a flexible web carrying a series of said cartridges in side-by-side relation along its length,
- (d) means for firing the gun by striking the projectile to separate it from the shell and propel it through the barrel,
- (e) means for striking the separated shell to propel it laterally, and
- (f) means for advancing said web longitudinally in timed relation to the operation of means (d) and (e) to bring successive cartridges to the firing position,
- (g) said shell being cylindrical element and said projectile having a stem extending rearwardly through and beyond said element, said projectile stem and shell being configured to interlock in frictional, readily separable, relationship.

15. A toy gun comprising:

- (a) a barrel,
- (b) a simulated cartridge comprising a projectile and a simulated shell separably associated with it,
- (c) means for supporting the cartridge in a firing position adjacent to the rear end of the barrel, said means including a flexible web carrying a series of said cartridges in side-by-side relation along its length,
- (d) means for firing the gun by striking the projectile to separate it from the shell and propel it through the barrel,
- (e) means for striking the separated shell to propel it laterally, and
- (f) means for advancing said web longitudinally in timed relation to the operation of means (d) and (e) to bring successive cartridges to the firing position,

11

(g) said cartridge supporting means comprising a guide housing, and said web having an apertured fin therein, said web being insertable into said housing for engagement thereby, said cartridge being supported within said aperture.
